[57] CLAIM

The ornamental design for a combined plate and utensil holder, as shown and described.

DESCRIPTION

FIG. 1 is a top, front, left side perspective view of a combined plate and utensil holder, showing our new design;

FIG. 2 is a left side elevational view thereof, the right side being a mirror image thereof;

FIG. 3 is a top plan view thereof;

FIG. 4 is a front elevational view thereof; the rear elevation being a mirror image thereof; and,

FIG. 5 is a bottom plan view thereof.
